UNITED STATES PATENT OFFICE

2,478,553

MANUALLY OPERATED PRESSURE
INTENSIFYING MEANS

Herbert J. Willmott, Beverly, Mass., assignor to
United Shoe Machinery Corporation, Flemington, N.J., a corporation of New Jersey

Original application August 4, 1943, Serial No.
497,415, now Patent No. 2,379,944, dated July 10,
1945. Divided and this application December
21, 1944, Serial No. 569,123

6 Claims. (Cl. 60—54.5)

1

This invention relates to mechanism by which pressure may be applied to work, as, for example, to retain it in place to receive the action of a tool. It is herein disclosed as embodied in a drilling machine, where it clamps in place a shoe-heel in which a plurality of passages are drilled simultaneously. This machine is as disclosed in the application for Letters Patent filed in my name in the United States Patent Office on August 4, 1943 and bearing the Serial No. 497,415. Of said application, which has matured into Letters Patent of the United States No. 2,379,944, granted July 10, 1945, the present case is a division.

In the machine of the parent application, a pressure device in the form of a clamping arm is successively moved by a force applied by the operator through a treadle into contact with heels upon a support, in preparation for the operating movement of a gang of drills. The displacing force of the drills upon the work is too great to be resisted readily by the operator, and the present invention has as an object the multiplication of the force which the operator may exert without undue effort, this being without the introduction of power mechanism. In the attainment of this object, there is combined with a pressure device, a member, as a treadle movable by the operator, mechanical means having elements through which said device may be brought directly into contact with the work to apply thereto preliminary pressure, and fluid-pressure mechanism having elements other than those included in the mechanical means and movable relatively to each other by said mechanical means to impart to the device increased final pressure-movement. In the pressure mechanism there are preferably a co-operating cylinder and piston, one connected to the member and the other to the device, between which cylinder and piston there is produced, after preliminary pressure-movement of the member, relative movement to cause the final pressure-movement of the device. More specifically, the treadle is yieldably connected to the pressure device, so its movement may be continued after contact of said device with the work, and the treadle is also connected to the cylinder. This cylinder is movable along a stationary head, and through the head the piston is movable by the treadle to create in the cylinder increased final pressure to be transmitted to the device. The head furnishes the sole guide for the cylinder and piston.

In the accompanying drawings,

Fig. 1 shows in front elevation a drilling ma-

2

chine, with which is associated the pressure mechanism of the present invention;

Fig. 2 is a side elevation thereof; and

Fig. 3, an enlarged sectional detail of the fluid-pressure elements on the line III—III of Fig. 2.

Upon a frame 52 is carried a holder D by which the work, such as a heel, may be clamped to receive the action of drilling mechanism A in which drills 58 are contained in chucks K. The chucks are rotatable on a reciprocating slide 54, they being driven through shafts X from power mechanism B controlled by clutch mechanism C. The breast of the heel being operated upon rests on a supporting bar 386 of the holder D, with the edge of its cup against an abutment-plate 388, through openings in which the drills pass. It is centered upon the bar in the correct relation to the plate-openings by fingers 398, 398, movable yieldably against opposite sides of the heel by connection to a treadle 362 fulcrumed at the bottom of the frame about a spindle 363. To resist the displacing force of the drills, as they pass through the plate and enter the heel, the holder D includes a pivoted arm 418 having a fork 420 for engagement with the back of the heel, and exerting a force having components which both hold the heel upon the bar 386 and against the plate 390.

To bring the fork 420 into engagement with the heel and apply thereto at least preliminary pressure, the treadle 362 is connected by a link 479 to the center of a toggle-lever 470, 472, the link 472 being fulcrumed at a relatively fixed point, and the link 470 being joined to an arm 468 fast upon a shaft 460 rotatable in the frame. A second arm 462 is secured to the shaft, and has a roll 464 lying in a slot 466 in an arm 416 fast upon a shaft 412. An arm 425 is free to turn about the shaft 412, and is joined by a torsion-spring 426 to the arm 416. A link 424 joins the arm 425 to a projection 422 from the heel-clamping arm 418. Depression of the treadle 362 by the operator will straighten the toggle-lever 470, 472 to turn the shaft 460, and through the arms 462 and 416, the spring 426, the arm 425 and the link 424 will oscillate the arm 418 to bring the fork 420 into engagement with the heel upon the support. The yield of the spring 426 permits continued depression of the treadle after such engagement.

Since the displacing force exerted upon the clamped heel by the advancing drills 58 is comparatively great, the operator, to resist this, might be called upon to apply to the treadle 362 a force 55 too heavy to be exerted readily. I have, there-

fore, utilized the final movement of the treadle acting through hydraulic mechanism W to increase the pressure upon the work and give a final clamping effect. The generally horizontal arm 425 upon the shaft 412 is extended at 540 and divided to receive between its separated arms a cylinder 542 provided with a fluid containing cylindrical chamber the lower end of which is formed by a face or pressure area 543. Entering this cylinder from above is a tubular member 544, which acts as a guide for the associated reciprocating elements and furnishes a head for the cylinder. The member 544 is supported upon the frame by a bracket 546, upon which it is pivoted. At its under side the member 544 has a cupped washer 548 for the retention below it in the cylinder of a body of oil or other fluid, and through the bottom of its reduced stem 549 into the cylinder are opposite openings 550, 550.

Beside the treadle 362, turning about the spindle 363, is a transmitting arm 552. Rising from this arm is a yoke 554 having depending from its upper cross-arm 556 a rod 558, which fits within the tubular stem 549 of the member 544 and furnishes the active piston of the mechanism. This piston has a face or cross-sectional pressure area 553 substantially less than that of the cylinder 542. The arm 552 is held up normally by a tension-spring 564 to a point determined by a stop-screw 566, threaded vertically through it and contacting with a portion of the frame. At this time, the lower end of the rod 558 is just above the stem-openings 550. Pivoted to the arm 552 is a link 568, at the upper end of which is a vertical slot 570. This receives a lateral projection 572 from an arm 574 fast upon the shaft 460 with the arms 462 and 468.

With a heel in place on the breast-bar 386, the operator depresses the treadle, causing the movement of the centering members 398 and the clamping member 418 into engagement with the heel. As the cylinder 542 is lowered in consequence of the treadle-depression, the contained oil passes idly through the openings 550 in the stem 549. When preliminary pressure has thus been applied to the heel, the torsion-spring 426 yields to permit the continued motion of the treadle, though that of the rod 424, which actuates the member 418, has stopped. As the toggle-lever 470, 472 is being straightened by the continuing depression of the treadle, the shaft 468 is turned clockwise, lowering the arm 574 and shifting the projection 572 idly along the slot 570 in the link 568. Just before the movement of an arm 490 on the shaft 460 causes, through a link 492, the tripping of the clutch of mechanism C to produce the action of the drills upon the heel, the projection reaches the lower extremity of the slot. This depresses the link 568, and therefore the arm 552, yoke 554 and piston 558. This at once closes the openings 550 and, until the completion of the treadle-depression, the piston acts to compress the oil in the lower portion of the cylinder 542. Because of the ratio of the areas of the rod and cylinder, the force exerted upon the treadle is greatly multiplied, and this is transmitted through the cylinder and the link 424 to the arm 418 to apply an adequate clamping force to the heel with relatively little effort on the part of the operator.

Having described my invention, what I claim as new and desire to secure by Letters Patent of the United States is:

1. In combination with a movable device for applying pressure to a work piece, a manually operated member, means comprising a series of elements successively linked to one another and constructed and arranged yieldingly to connect said member to said device to cause the device to be forced with yielding preliminary pressure against said work piece in response to movement of said member, relatively movable parts forming a chamber constructed and arranged to house a fluid, one of said parts being yieldingly connected through elements of said means to the manually operated member and also being connected through elements of said means to said device and having a face against which said fluid under pressure may exert force, and transmitting mechanism operatively connected to a second of said parts, said second part having a face which is considerably smaller than said face of said one part and is constructed and arranged to be moved against the fluid in said chamber by said transmitting mechanism upon continued movement of the manually operated member thereby raising the pressure of the fluid in said chamber and applying through said one part a heavy final pressure to the device.

2. In combination with a movable device for applying pressure to a work piece, a manually operated member, means comprising a series of elements successively linked to one another and constructed and arranged yieldingly to connect said member to said device to cause said device to be forced with yielding preliminary pressure against the work piece in response to movement of said member, relatively movable parts, comprising a cylinder and a piston, constructed and arranged to house a fluid, said cylinder being yieldingly connected through elements of said means to the manually operated member and also being connected through elements of said means to said device and having a face against which said fluid under pressure may exert force, and transmitting mechanism operatively connected to said piston, said piston having a face which is considerably smaller than that of the cylinder and is constructed and arranged to be moved against the fluid in said cylinder by said transmitting mechanism upon continued movement of the manually operated member beyond its position in which the work piece is preliminarily clamped thereby raising the pressure of said fluid in said cylinder and through said cylinder actuating said device to apply a heavy final pressure to said work piece.

3. The combination with a movable device through which pressure may be applied, of a treadle movable by the operator, means connecting the treadle yieldably to the device and permitting continued movement of said treadle after contact of the device with the work, a fluid containing cylinder which is operatively connected to the device for movement in a predetermined direction and has a relatively large face against which fluid pressure is applied for moving said cylinder in said direction, a stationary head for the cylinder, and a piston having a relatively small fluid engaging face movable through the head by the treadle to create pressure in the cylinder to be transmitted thereby to the device, the head furnishing the sole guide for the cylinder and piston in their movement.

4. The combination with a movable device through which pressure may be applied, of a treadle movable by the operator, a transmitting arm movable by the treadle, a shaft provided with a plurality of arms, means for connecting one of

the shaft-arms yieldably to the device, means connecting another of the shaft-arms to the transmitting arm, a fluid containing cylinder which is movable with the device and has an effective pressure area, and a piston which is movable in the cylinder by the transmitting arm and has an effective pressure area considerably less than that of the cylinder.

5. The combination with a frame, of a pressure device and a treadle movable thereon, a fluid containing cylinder which is connected to the pressure device and has an effective pressure area, a tubular head carried by the frame, said head being arranged within the cylinder and the cylinder being movable along it, a piston which is movable in the head and which has an effective pressure area considerably less than that of the cylinder, and means for connecting the pressure device to the treadle for movement thereby and including means to permit the piston to remain at rest and thereafter to move said piston.

6. The combination with a frame, of a pressure device and a treadle movable thereon, a fluid containing cylinder which is connected to the pressure device and has an effective pressure area, a tubular head which is carried by the frame is arranged within the cylinder and serves as a guide

along which said cylinder may move, there being an opening in the head through which fluid may flow during movement of the cylinder, a piston movable in the tubular head and closing the head-opening in its initial movement, said piston having an effective pressure area considerably less than that of the cylinder, and means for connecting the pressure device to the treadle for movement thereby and including means to permit the piston to remain at rest and thereafter to move said piston to cause fluid pressure in said cylinder to increase thereby moving said cylinder and accordingly said pressure device.
